UNITED STATES PATENT OFFICE.

MARTIN V. B. ETHRIDGE, OF BOSTON, MASSACHUSETTS, ASSIGNOR OF NINE-TWENTIETHS TO ALBERT LEAVITT, OF SAME PLACE.

MACHINE FOR LABELING CANS.

SPECIFICATION forming part of Letters Patent No. 398,775, dated February 26, 1889.

Application filed October 17, 1887. Serial No. 252,681. (No model.)

To all whom it may concern:

Be it known that I, MARTIN VAN BUREN ETHRIDGE, of Boston, in the county of Suffolk and State of Massachusetts, have invented a new and useful Machine for Labeling Cans, of which the following is a specification, reference being had to the accompanying drawings, in which—

Figure 1 is a front elevation, and Fig. 2 a plan, of one of my machines. Fig. 3 is a sectional elevation on line 3 3 of Fig. 2. Fig. 4 is an end elevation of Fig. 3. Figs. 3 and 4 illustrate the pasting apparatus; and Figs. 5, 6, 7, 8, and 9 are details illustrating the details of construction of the pasting apparatus. Fig. 10 is an inside elevation from the arrow 10 of Fig. 2, illustrating a portion of the mechanism for carrying the can over the pasted label. Fig. 11 is an end elevation of Fig. 10. Figs. 12, 13, and 14 illustrate the construction of the carrier which supports a pack of labels, Fig. 14 being a plan and Figs. 12 and 13 sections on lines 13 13 and 12 12 of Fig. 14. Fig. 15 is a detail illustrating the locking mechanism by which the pack-carrier is locked when the can is rolled over it. Fig. 16 is an end view, partly in section, illustrating the can-carrier. Fig. 17 is a sectional elevation on line 17 of Fig. 16. Fig. 18 is a plan of Fig. 17, partly in section. Figs. 19, 20, and 21 are details illustrating the mechanism for opening and closing the clamps which connect the can with its carrier. Fig. 22 is a side elevation, and Fig. 23 a plan illustrating the can-carrier in position to take a can from the chute. Fig. 23^a is a detail illustrating the locking device for the front stop. Fig. 24 is a sectional elevation on line 24 of Fig. 23; and Fig. 25 is the same, but in a different position. Fig. 26 is like Fig. 24, except that the machine has been adjusted for cans of smaller diameter. Figs. 27, 28, and 29 are details illustrating the middle or centering stop. Fig. 30 is a plan, and Fig. 31 a sectional elevation on line 31 of Fig. 30, illustrating the can-discharging apparatus. Fig. 32 is a detail showing a part of the discharging-chute. Figs. 33, 34, and 35 are details illustrating the locking device for locking the ring which carries the packs of la-

bel. Fig. 36 illustrates the mechanism for giving the ring or wheel its proper motions. Fig. 37 is a front view, and Fig. 38 a side view, illustrating the device used for smoothing and working the paste into the label and to keep the label from curling.

My invention is a machine for applying labels to cans; and it consists, mainly, of a pack-holder for receiving a number or pack of labels, a pasting apparatus by which the upper label of the pack is pasted, and a can-carrier by which the can is rolled over the pasted label, organized by suitable connecting mechanism to form a machine by which the labels are pasted one after the other and the pasted label and can brought into proper relation, and the can rolled over the pasted label, or vice versa—that is, the pasted label passed under the rolling can.

The main novelty of my machine is a can-carrier consisting, essentially, of a pair of clamps which open during the back-stroke of the can-carrier to receive the can, then close upon the can and revolve with the can during the forward stroke of the can-carrier when the can is carried over the pasted label. While I have contemplated a can-carrier on this principle which retained the can until near the completion of its back-stroke—that is to say, discharged the labeled can near the same position in which the can to be labeled was fed into it—I have found it better where the can is to be fed automatically rather than by hand to the can-carrier to cause the carrier to take the can at one end of its stroke and discharge it at the opposite end, as in the machine shown in the drawings. I have also contemplated a pack-carrier which should reciprocate between the pasting device and the can-carrier, but prefer to use a number of pack-carriers moving in a circle, as shown in the drawings.

It will be clear that the cans may be fed to the can-carrier by hand; but as this requires the constant attention of the operator I prefer to use an automatic contrivance by which the cans are brought successively into proper relation with the clamps of the can-carrier.

In the drawings, A A' represent the base and frame of the machine.

B is a wheel which rotates intermittently and carries a number of plates, b, each plate having secured to it a block or pad of labels. The labels in packs are secured to a stiff backing of pasteboard, forming the ordinary block or pad gummed at one edge, as will be clear without further description. The stiff backing of this block or pack of labels is secured to a plate, b, by means of the edge gage b' and the clamps b² b³. Clamps b² are moved toward and from each other by the right and left screw b⁴, and the clamp b³ is moved toward and from the edge gage b' and held by pin or clamp screw, as will be clear without further description from Figs. 13 and 14. The plate b is fast to spindle b⁵, which is socketed in a sleeve, 1, clamped to the ring B, and this spindle b⁵ is elevated to bring the upper label, after it is pasted, into contact with the can by means of a cord and spring or the like, as indicated in Figs. 10, 11, and 13, in which the cord is marked 2 and the spring 3, the cord being secured to the spindle b⁵ and also to spring 3, which is fast at one end to wheel B. The plate b is normally in the position shown in Fig. 12, and is held in this position against the resistance of spring 3 by a set-screw, b⁶, mounted in a boss, 5, in sleeve 1, and the set-screw is held in contact with the spindle b⁵ by a spring, b¹⁰, (see Fig. 15,) which is secured to arm b⁹ of the set-screw b⁶ and also to the wheel B. When the upper end of lever f' is moved into the position shown in dotted lines in Fig. 15, the hook b⁸, fulcrumed to it, rides on a rack, b¹¹, in wheel B, and when the lever returns to the position shown in full lines in Fig. 15 the hook b⁸ drops into engagement with arm b⁷ and set-screw b⁶ and withdraws the set-screw sufficiently from the spindle b⁵ to allow the spindle with its plate to move upward under stress of spring 3. It will now be clear that the label-carriers b are brought successively by the motion of the ring or wheel B into proper relation with the pasting apparatus and the can-carrier.

While I have shown only one pasting apparatus and can-carrier, it will be obvious that there is room upon the wheel or ring B for a second pasting apparatus and can-carrier; but as the paste I prefer to use works better if it is spread upon the label about a minute before the label is pasted upon the can I prefer to use only one pasting apparatus and can-carrier, as shown in the drawings, and to revolve the ring or wheel B in the direction shown by the arrow in Fig. 2, as this gives time for the paste to get into proper condition before it is applied to the label and before the label is stuck.

In Fig. 12 the spindle b⁵ is shown as controlled by a set-screw, b⁶, which prevents the operation of the cord and spring shown in Fig. 13 until the set-screw is loosened. By this means the upper surface of the block of labels is prevented from rising until the set-screw is automatically loosened at the proper time.

The pasting apparatus is best shown in Figs. 3 to 9, inclusive. It consists of a vessel, D, containing paste, the mouth of which is closed by roller d, with the usual adjusting-plate, d', too familiar to require further description. This vessel D is supported upon the stud d², which is fast to a horn or arm projecting from slide d³, which slide moves in ways fast to the upright A'. (See Figs. 3 and 4.) Slide d³ is reciprocated by lever d⁴, a stud from the slide entering the forked end of the lever, as shown in Fig. 3. The lever d⁴ is oscillated by means of the crank-pin projecting from the gear-wheel and entering the slot in the lever d⁴, as will also be clear from Fig. 3. The pinion d⁵ meshes with a rack, d⁶, which rack is rigidly connected to the upright A', so that the pinion d⁵ revolves as the paste-fountain is traveled back and forth. The pinion d⁵ is also connected to a hub or trunnion fast to one side of the paste-fountain by a spring-brake, (shown in detail in Fig. 6,) so that when the paste-fountain is traveled from left to right (see Fig. 3) it is tipped, as shown in dotted lines on the right of Fig. 3, until its stop d⁷ strikes the cross-piece d⁸, thereby bearing the roll d of the paste-fountain into close contact with the upper label of the pack. The stop d⁷ is a screw, in order to make it adjustable. When the paste-fountain is carried from right to left, the pinion d⁵, acting through the friction-brake shown in Fig. 6, tips the fountain until stop d⁷ comes in contact with cross-piece d⁸, thereby causing the roll d to clear the pack of labels. The roll d has pinion d¹⁰ connected with its shaft by means of the ratchet and pawl, as shown in Fig. 7, and pinion d¹⁰ meshes with pinion d⁹, which is driven by the rack d⁶, as already described, and as fully shown in Fig. 8. In this way the roll d is revolved only in the forward stroke of the paste-fountain; but pinion d¹⁰ pulls the ratchet over the pawl on the back-stroke without revolving roll d.

The can-carrier F is a bracket projecting from slide f, which moves in ways in the upright A', Figs. 10 and 11. This slide f is reciprocated by lever f', as will be clear from Fig. 10, and substantially as before described as to the slide-carrying paste-fountain. The can-carrier has two clamps, f², each mounted upon a spindle, so that the clamps cannot only be moved nearer together to clamp the cans and farther apart to release the cans, but can also be revolved to roll the can over the pasted label. The pinions f³ are connected to the spindles of the clamps f² by a friction-brake, as shown in the right of Fig. 16, and these pinions mesh with the racks f⁴, so that when slide f is moved forward and back by lever f' the clamps f² are rotated; but this rotation is not positive in the clamps f² because of the friction-connection between the pinions f³ and those clamps. The importance of this is that I am enabled thereby to give the clamps f² and the cans held between them a slightly greater surface speed than

would be necessary to simply roll the pasted label about the can and thereby get a tension upon the label, which not only wraps the label tightly about the can, but also prevents the wrinkling and gives smooth and perfect work.

The clamps f^2 are separated to receive the can by means of a collar, f^5 , and the cam f^6 . (Shown enlarged in Figs. 19, 20, and 21.) The 10 collar f^5 surrounds the spindle of the clamp f^2 , and a projection from collar f^5 engages cam f^6 near the end of the back-stroke of the slide f , thereby separating the clamps f^2 , so that a can can be inserted between them; but 15 as these projections from collar f^5 pass farther back they pass by a shoulder on the cams f^6 , as shown in Fig. 17. In Fig. 19 the collar is shown just before it has traveled far enough back for its projections to pass by a shoulder 20 on the cams f^6 , dotted lines in this figure indicating different positions taken by the collar in its travel, and the clamps f^2 are thrown forward by springs, (shown on the right of Fig. 16,) so as to seize the can between them. 25 As this brings the projections on the collars f^5 in line with the cams f^6 , I mount the cams on studs and counterweight them, as shown in Figs. 17, 18, and 19, so that the cams will be moved out of the way on the forward stroke 30 of the can-carrier, as indicated in dotted lines in Fig. 19.

The collar f^5 and cams f^6 are adjustable with the clamps f^2 for different lengths of cans, as follows: The threaded sleeve f^7 passes 35 through a nut fast to collar f^5 , so that by turning sleeve f^7 the collar f^5 and its clamp f^2 and the spindle of that clamp are moved lengthwise of the spindle. A cam, f^6 , is adjusted by nut f^8 on the screw-stud upon which 40 that nut travels. (Shown clearly in Fig. 20.) The sleeve f^7 also serves as a stop to prevent clamp f^2 moving too far in when there is no can between the clamp. After the can has been carried over the pasted label, and 45 the label wrapped tightly around it, one of the collars f^5 , which, as above explained, is mounted on the spindle of a clamp, f^2 , (see Fig. 16,) engages with a cam, f^9 , mounted on the rack-frame, as shown in Figs. 50 17 and 18, and this cam f^9 is formed with an inclined face, so that when the collar f^5 engages it the collar and the clamp f^2 , connected to the collar, are pulled away from the can against the force of spring 6 (see Fig. 16,) 55 and the can is thereby released and falls, say, one-quarter of an inch and lies in the chute K, hereinafter referred to. The can-carrier now travels in the opposite direction, and to prevent the clamps f^2 from seizing the can 60 and carrying it back to the position indicated in the right of Fig. 17 a spring-catch, 7, is inserted in the face of cam f^9 , over which the projection 8 on collar f^5 rides, so that on the beginning of the back-stroke of the can-carrier one of the clamps f^2 is held away from 65 the can, thereby allowing the can to remain in the chute. The cam f^9 moves with the

can-carrier during the back-stroke until the projection 8 on the collar f^5 clears the spring-catch 7, as indicated in dotted lines in Fig. 17, 70 when the clamps f^2 are far enough away from the can to allow the clamps to return to position without engaging the can lying in the chute.

As will be obvious, the cans might be fed 75 into and taken out of the can-carrier by hand; but I deem it better to provide automatic devices by which the cans can be fed automatically to the can-carrier and delivered from the machine after they are freed from the can-carrier. A number of cans are placed upon a chute, G' , Fig. 10, and rolled down that chute into the chute G , where they are arrested, the lower end of the chute forming one stop and the cross-piece upon the finger g another stop, 80 while a third stop, g , prevents the forward motion of the can when pressed down upon the pasted label, as shown in Fig. 24. These stops also center the cans in accurate relation to the clamps f^2 of the can-carrier. When 90 the can-carrier moves forward with the lowermost can, the finger g is moved out of the way against the force of its spring g^2 and is returned to place by that spring as soon as the can clears it. The first motion of finger 95 g depresses stop g^3 , which has an arm fast to the shaft, to which finger g is also fast, and thereby allows the arrester g^4 to come in contact with the can next above the lowermost one, and thereby stop the further descent of 100 the row of cans.

The finger g is actuated as follows: A horn, h , projects from the main frame of the can-carrier, as shown in Figs. 17 and 22, and this horn carries a rod, h' , which stands in relation to an ear, h^2 , on the front stop carried by the fingers g , as shown in Figs. 22 and 23, so that when the can-carrier moves forward with the can the rod h' bears against the ear h^2 , and thereby causes the fingers g to move upward against the force of the spring g^2 , thus 110 allowing the lowermost can free passage under the stop carried by the fingers g . While the can itself might lift the fingers g , yet, as the label has not become fully dried, it is 115 deemed better to have the special contrivance for preventing the rubbing of the front stop on the can. The rod h' is adjusted for different sizes of cans by means of the slot in the upper part of the horn h and the adjusting-screw which passes through a lug on the horn h . On the return-stroke of the can-carrier the rod h' rides over the ear h^2 , as indicated 120 in dotted lines in Fig. 22, and falls into place to engage the ear h^2 when the can-carrier gets 125 to the position to seize a can. The fingers g are locked in place by means of the spring-bolt h^3 entering a hole in a segment, h^4 , rigidly attached to one of the fingers g . This spring-bolt is carried by a collar, h^5 , which is 130 held by a set-screw to the shaft to which the fingers g are fast. The can h^6 is fast to a projection on the frame of the can-carrier, as shown in Figs. 23, 23^a, and 17, and this cam

engages with the bolt h^3 as the can-carrier nears the lowermost can and withdraws the bolt h^3 from the segment h^4 , as shown in Figs. 23 and 23^a, leaving the fingers g free to be moved by the rod h' , as above described.

The labeled cans are carried out of the machine as follows: The racks f^4 are narrowed near their inner ends, as shown in Fig. 30, to receive the movable end k of the final chute K , so that when the pinions f^3 come to the narrow parts of the racks f^4 they bear upon the parts k and depress the swinging parts $k' k'$ of the final chute K , as shown in Fig. 31. The can is then released by the clamps f^2 and drops slightly into a depression shown between the parts k and k' , and as the can-carrier and its pinions f^3 move back the parts $k' k$ spring up into the position shown in the dotted lines in Fig. 31, and the can rolls down the chute K . k' is a single piece of sheet-steel continuous with the bottom of the chute K , but has an auxiliary spring, k^2 , to aid in lifting it.

The ring or wheel B is rotated by means of the lever J , which is oscillated substantially as before described in relation to the levers d^4 and f' . This lever J carries slide j , upon which is the spring-pawl j' , which engages with notches j^3 in the periphery of the ring B , so that the ring is moved from notch to notch by the motion of the slide j and its pawl j' . The ring B is locked in place by the spring-bolt l , which is fast to the upright A^4 , as shown in Figs. 33, 34, and 35, and this spring-bolt is withdrawn at the proper time by the cam l' , fast to the intermediate gear, A^5 . This locking device carries the stop-pawl l^2 , which prevents all possibility of the backward motion of the ring.

In my machine as shown in the drawings the front corner of each pack of labels would rub against the under side of the lowermost can as the pack of labels came under the feeding-chute were it not for the rock-shaft m , which by its motion raises the lever m' at the proper time and elevates the chute G clear of the advancing pack of labels. This lever m' is adjustable, as indicated on the right of Fig. 10, so that when the chute G rests upon lever m' the lowermost can is in place over the front edge of the pasted label, which is then forced into close contact with the lowermost can by the spring and cord which elevate the pack-carrier b . The rock-shaft m (see Fig. 10) is rocked by lever m^2 and its cam m^3 , this lever and cam being clearly shown in Fig. 1. This rock-shaft and its lever are also shown in plan in Fig. 36.

The ring B is kept from sagging by the trucks n , and to the frame that supports these trucks I attach swinging carriers n' , each carrying a pad or wiper, n^2 , which hangs in such relation to the pasted label that the label will slightly raise the pad as it passes under it, so that the paste upon the label will be smoothed and worked into the label and the label will

also be kept from curling and made ready for application to the can.

As the pinions f^3 vary in size to suit the varying diameters of the cans, I have shown the racks f^4 adjustable on their frames by means of two holes through the frame, the racks being supported by a clamp-screw through the upper hole (shown in Fig. 17) when the smaller-sized cans are to be labeled.

The operation is as follows: The cans are fed by the attendant into the chute G' and rolled into the chute G , while the lowermost can is stopped and centered by the stops $g g$ and the lower end of the chute G' . The can-carrier at the end of its back-stroke seizes the can by means of the clamps f^2 , as above explained, and moves forward with the can, stop g being moved out of the way. Just before the can commences to move forward with the can-carrier the pack of labels is pressed up under the can by means of the spring and cord on the block-carrier, and as the can-carrier moves forward the can is revolved by means of the revolving clamps and their pinions, and as the diameter of the can is slightly greater than the diameter of the pinions the surface of the can tends to slide the uppermost label on the pack of labels below it; but the friction of this moistened label upon those below it and the gumming at the front end of the pack together prevent the uppermost label from sliding on those below it. This causes the can to stretch the uppermost label, thereby preventing wrinkles. When the strain exceeds the proper amount, the friction device which connects the clamps and the pinions allows the pinions to move without rotating the can. Moreover, the label has already swelled from the moisture of the paste which has been applied and wiped in and smoothed by the passage of each label from the pasting device under the wipers and by reason of the paste being applied for about a minute before the label is applied to the can, so that after the label is applied it tends to shrink in drying, making it hug the can more closely. When the label has been thus wrapped about the can, the can-carrier has brought the can over the curved depression between the pieces $k' k$ of the chute K , and the can is then released and carried down the chute K .

It will be observed from the drawings that the line of the sliding can-carrier is not quite parallel to the surface of the pack, and in practice I prefer to have the surface of the can slightly above the surface of the pack after the can has traveled upon the pack for a few inches—that is, the pack is, of course, pressed firmly up under the can—the can being prevented from lifting by the weight of the chute G and the other cans in that chute and by the center supporting-stop, g ; but the axis of the can moves forward over the pack in a plane which slants slightly away from the surface of the pack, so that after the can has traveled three or

four inches the uppermost label (one end of which is wrapped partly about the can) is slightly elevated from those labels below it. This is an important feature for several reasons, the chief of which is to properly strain the label, so that it may be always wrapped smoothly and tightly about the can. This slant also carries the labeled can well above the labels in the pack toward and over which the can is carried.

The main features of the novelty of my invention reside in pasting the labels at such a distance from the point where they are applied to the can as to give the label an opportunity to swell from the moisture of the paste and generally to bring the pasted label into what is called the "proper temper;" and I am the first, so far as I know, to devise a machine in which this can be done.

Another feature of novelty in my machine is the straining of the label by rolling the can over it, the amount of strain depending upon the adjustment of the friction device which connects the can-clamps with the power by which they are revolved. This feature is also wholly new with me, so far as I have any reason to believe.

I am aware of Pritchard's patent, No. 252,137, of January 10, 1882; Patte's patent, No. 106,724, of August 23, 1870, and Hursch's patent, No. 360,694, of April 5, 1887, and disclaim all that is shown in them.

What I claim as my invention is—

1. The can-carrier F, provided with one or

more clamps, f^2 , each mounted on a spindle 35 provided with a pinion, f^3 , which is connected to the spindle by a friction-brake, and one or more racks, f^4 , the spindles of the clamps f^2 being movable endwise through the pinions f^3 , all arranged and operating substantially 40 as and for the purpose set forth.

2. The herein-described combination of a pack-carrier with pasting apparatus and the wiper n^2 , mounted to engage the pasty surface of the pack on the carrier, all arranged 45 and operating substantially as and for the purpose set forth.

3. In combination, the endless pack-carrier, pasting apparatus, and can-carrier, all arranged and operating substantially as described.

4. The pack-holder b, in combination with the clamp-screw b^6 and a cord, 2, and spring 3, or its equivalent, for elevating the pack-holder, and means, substantially such as described, for tightening and releasing the clamp.

5. In a can-labeling machine, a can-carrier moving in guides, in combination with a pack-holder arranged to bring the surface of 60 the pack when in the holder slightly inclined to the guides of the can-carrier, all substantially as and for the purpose specified.

MARTIN V. B. ETHRIDGE.
